Fig. 3

A technical line drawing of a mechanical assembly. On the left, a large cylindrical component is mounted on a frame. A mechanical detail, labeled '15' and '16', is attached to the side of this cylinder. A long horizontal beam extends from the cylinder towards the right. On the right side, there is a complex arrangement of mechanical parts, including a vertical cylinder and a horizontal beam. The drawing is a black and white technical sketch.

UNITED STATES PATENT OFFICE.

JOHN C. McDONALD, OF NEW YORK, N. Y.

RAILWAY-TRAIN-CONTROLLING SYSTEM.

1,151,027.

Specification of Letters Patent. Patented Aug. 24, 1915.

Application filed June 26, 1913. Serial No. 775,879.

To all whom it may concern:

Be it known that I, JOHN C. McDONALD, a citizen of the United States, and a resident of New York, in the county of New York 5 and State of New York, have invented certain new and useful Improvements in Railway-Train-Controlling Systems, of which the following is a specification.

My invention relates to improvements in railway train-controlling systems, and particularly combined automatic signal, train-stop, and speed-control systems, and comprises a system equally applicable to roads operated by electric energy derived from a 15 stationary generating plant, and to roads employing individual power units for each train, such as steam locomotives and storage battery motor cars.

My invention comprises stationary signals and signal-circuits and controlling instruments therefor, combined with train-control circuits, which are carried by the trains and are arranged to be made effective for the control of the trains by contact of 25 contact shoes or the like carried by the trains with sectional conductors located along the track; and my invention further comprises means whereby the speed of trains is controlled; all as hereinafter described and 30 pointed out in the appended claims.

The objects of my invention are to facilitate the operation of railways; to reduce the liability to collisions; to provide effective means for positively stopping trains; to 35 prevent entry thereof into blocks which are already occupied, or the signals of which are at danger; to provide simple means for the automatic control of train speed; to provide a system which may be applied readily and 40 at relatively small expense to existing roads employing separate power units, such as steam locomotives, for the individual trains; and generally to make the circuits and apparatus of the systems simple and reliable and 45 to cause such circuits and apparatus to afford ample protection to trains.

I will now proceed to describe my invention with reference to the accompanying drawings, and will then point out the novel features in claims.

In the drawings, Figure 1 is a diagrammatic view showing circuits and instruments for one track of a double track railway, the direction of normal progress along such 55 track being indicated by an arrow. Fig. 2

is a diagram illustrating an alternative arrangement of circuits, this figure illustrating the fact that the controlling circuits of the secondary relay need not pass through contacts of a secondary relay of a block in advance as well as through contact points of a primary relay of a block in advance. Fig. 3 is another diagrammatic view illustrating the fact that the secondary relays may operate upon normally closed circuit instead of 60 upon normally open circuit. Fig. 4 is a view illustrating diagrammatically the control of a locomotive throttle valve and brake valve by the holding coil H of the train circuit. 70

In the embodiments of my invention herein illustrated and described, one, and preferably both, of the two parallel rails of each track, are insulated from the ground and divided into block sections, such sections being 75 insulated from each other; and track circuits are provided which include the insulated rail sections, by which track circuits suitable relays, circuit breakers, or switches, controlling signals and controlling the automatic stop circuits, are operated as hereinafter described. But it will be understood that the said relays or automatic switches may be operated by any of the well known equivalents for track circuits, so that track circuits are 80 not fundamentally required in my system; though they are convenient. 85

Referring first to Fig. 1; T^1 , T^2 , etc., designate block sections of the track rails, insulated from the ground and from each other; 90 A^1 , A^2 , etc., represent suitable track circuits, batteries or electric generators connected to the track rails T^1 , T^2 , etc., respectively, so that the said batteries and their connections, with the rail sections T^1 , T^2 , etc., form track circuits adapted to be short circuited by the wheels of a car or train passing over the track. For each block a suitable main relay or switch MR^1 or MR^2 , etc., is provided, connected to the corresponding insulated rail 95 section T^1 , or T^2 , or T^3 , etc., as the case may be, by suitable conductors 1 and 2, the arrangement being such that the magnet of each main relay is normally energized; its operating track circuit, however, being arranged to be short circuited, and the magnet being therefore arranged to be deenergized, by the wheels and axles of a car or train passing on to the corresponding block. 100 Each main relay is provided with front con- 105

tacts 3 controlling, through suitable conductors 4 and 5, a safety signal S, and with rear contacts 6 controlling, through conductors 7 and 8, a danger signal D; current for the 5 operation of these signals being supplied by a signal battery or generator 9, of which there is one for each block. In Fig. 1 I have indicated that each of these signal batteries 10 is grounded on one side and have indicated each signal conductor 8 as extending from the corresponding rear contact of its main relay MR¹ or MR², etc., as the case may be, through its corresponding danger signal D to a caution signal C at the block next in 15 rear and thence to ground; there being, therefore, three signals at the entrance of each block, namely, a safety signal S, a caution signal C, and a danger signal D; but obviously the caution signals C may be 20 omitted, if desired.

It will be apparent that these signals will be operated as follows: When any particular block is clear, that is to say, when there is no car on that block, the magnet of the 25 corresponding main relay MR¹, or MR², etc., will be energized, and the safety signal S of that block will be displayed; but when there is a car on any block, the magnet of the main relay MR¹, MR², etc., as the case 30 may be, will be deenergized, through the short circuiting of the track circuit of that block by the wheels and axles of that car, and the danger signal D of that block, and the caution signal C of the block next in 35 rear, will be displayed, and the safety signal S of the block so occupied will not be displayed.

I will now proceed to describe the means, 40 entirely independent of the signal circuits just above described, for the positive control and stopping of the trains which may run into a danger block or past a danger signal. For this purpose, I provide, at a suitable point in each block, a contact rail 45 designated in the drawings by the letter L¹, or L², or L³, etc., as the case may be. These contact rail sections L¹, L², L³, etc., should be arranged parallel to the track rails and a short distance therefrom, and may be 50 on either side of the track. They should be so placed that a suitable contact shoe or other convenient contact device M carried by the locomotive or leading car of the train, will contact with such contact rail sections 55 as such locomotive or car passes such contact rail sections. The manner of support of such contact shoes M on the locomotive or cars is well understood, and is not necessary to be described here. The contact rail 60 sections L¹, L², etc., should have at least a length such that a car or train, when passing at the maximum speed over the track, will remain in contact with such contact rail section for a period long enough for the 65 operation of a train relay or switch also car-

ried by such locomotive or car. In most cases a length of ninety to one hundred feet for these contact rail sections L¹, L², etc., will be sufficient though a greater length is not objectionable, and in fact, the longer 70 these rail sections L¹, L², etc., are, the better; for the longer these sections are, the longer is the period within which the car or train is under absolute control of the automatic stop device.

Each locomotive or motor car is provided with a train relay or switch TR and with a train battery or generator TB. Normally this train relay is energized by current from battery TB through conductor 10 leading 80 to an axle bearing (and therefore the axle and its wheels) of the car, and thence to the magnet of the train relay and thence through conductor 11, shoe M and thence back to battery TB. When shoe M makes 85 contact with one of the contact rail sections L¹, L², L³, etc., the relay will be shunted out, as hereinafter described, and so deenergized. A circuit 13 from another train battery TB' passes through front contacts 14 90 of relay TR, and through a so-called "holding coil" H. This holding coil H controls suitable means for controlling or stopping the train; for example, and as illustrated in Fig. 4, it may control a throttle valve 15 95 and an air brake valve 16, the throttle valve being held open and the air brake valve closed so long as said coil is energized; while when said coil is deenergized, the throttle valve is closed and the air brake valve 100 opened, so shutting off power and applying the brakes.

In order that the relay TR may be deenergized, to effect the deenergization of the holding coil H, and therefore to bring the 105 train to rest, it is necessary that when the contact shoe M of the train is in contact with one of the contact rail sections L¹, L², etc., that contact rail section shall be electrically connected to one of the track rails 110 of the corresponding block and so through the wheels and axles to the conductor 10. To this end I provide at each block a secondary relay or switch SR¹, SR², SR³, etc., each such secondary relay having a rear 115 contact 17 which, when completed, connects conductors 18 and 19 leading from one of the track rails and from the corresponding contact rail section L¹, L², L³, respectively. Each such secondary relay has also a contact 20 controlling the circuit of the corresponding secondary relay of the block next in rear. To this end a ground connection G¹, or G², or G³, etc., is provided at each 120 block, a conductor 21 leading from such ground connection to rear contact 20 of the corresponding secondary relay of that block, through conductor 22 to that track rail of the block to which conductor 18 is connected, thence through conductor 18 to contact 17 130

of that relay, thence through conductor 19 to contact rail section L^1 , L^2 etc., of that block; and from such contact rail section a conductor 23 leads through a battery 24 to 5 other rear contacts 25 of the corresponding secondary relay of that block, and thence a conductor 26 leads to front contacts 27 of the main relay MR^1 or MR^2 , or MR^3 , as the case may be, of that block; from which 10 front contacts a further conductor 28 leads to a front contact 29 of a delay action relay DR^1 , DR^2 , DR^3 etc., of the block next in rear, whence a conductor 30 leads to the magnet of the secondary relay SR^1 , or SR^2 , 15 or SR^3 , as the case may be, of such block next in rear, and thence to a rear contact 31 of the main relay MR^1 , or MR^2 , or MR^3 , etc., of such rear block, and thence to a further ground G^1 , or G^2 , etc., of that block 20 next in rear. It will be seen that the circuits and connections are such that when the magnet of any main relay MR^1 or MR^2 , etc., is energized, the magnet of the corresponding secondary relay must be deenergized, 25 and the rear contacts of that secondary relay closed; but when the magnet of any main relay MR^1 or MR^2 , etc., is deenergized, the magnet of the corresponding secondary relay SR^1 , SR^2 , etc., may be energized, provided the contact of the corresponding delay action relay DR^1 , DR^2 , etc., be closed, 30 and provided the magnets of the main relay MR^1 , or MR^2 , or MR^3 , as the case may be, of the block next beyond, be energized, 35 and provided the magnet of the secondary relay SR^1 , or SR^2 , or SR^3 , as the case may be, of the block next beyond, be deenergized.

The delay action relays, or time relays, as they are sometimes termed, DR^1 , DR^2 , etc., are relays which close their contacts a determined interval after their magnets are energized. They may be of any suitable construction. As a diagrammatic representation of such relays, I have indicated 45 relays the armatures of which are retarded by dash pots. Each delay action relay is in a local circuit controlled by a rear contact of the corresponding main relay MR^1 , MR^2 , etc.

50 The operation of these train control and automatic stop circuits is as follows: Suppose a train to pass from block T^1 to block T^2 , the latter block being otherwise unoccupied, and block T^3 being unoccupied. As 55 the train enters block T^2 the main relay MR^2 of that block is operated, its front contacts being broken and its rear contacts closed, and thereby the danger signal D at the entrance of that block T^2 and caution signal C at the entrance of the block T^1 , are displayed, and the magnet of the corresponding delay action relay DR^2 is energized so that said relay closes its contact 29 after a predetermined interval; the secondary relay 60 SR^2 of the block T^2 is operated as soon as

contact 29 of relay DR^2 is closed, so that the connection of contact rail section L^2 to one of the track rails T^2 is broken at contact 17 of relay SR^2 ; therefore when, as the train passes on in block T^2 , its shoe M contacts with the contact rail section L^2 , the shunt circuit from the train battery TB through the shoe M, contact rail section L^2 , conductors 19 and 18, track rails T^2 , the wheels and axles, and conductor 10, is not completed, and therefore the magnet of train relay TR remains energized and the holding coil H does not operate. But should the speed of the train be so great that the train reaches the contact rail section L^2 before delay action relay DR^2 has closed its contact 29, then when shoe M contacts with contact rail section L^2 the shunt circuit around relay TR will be completed through contact 17 of relay SR^2 and relay TR will be deenergized, so arresting the train, which can proceed only when contact 29 of relay DR^2 is closed. By proper regulation of the speed of operation of the delay action relays, therefore, it is possible to limit the speed at which trains may move. When the train has passed completely into block T^2 , the magnet of the main relay MR^1 of block T^1 is energized, the danger signal D of that block is no longer displayed, and the safety signal S of that block is displayed, the caution signal C of that block remaining displayed since block T^2 is now occupied. The train in block T^2 is then protected in rear by the caution signal C of the block T^1 , and by the danger signal D of the block T^2 . Suppose, however, that when the train so passes into block T^2 , block T^3 is already occupied. In such case the caution signal C at the entrance of the block T^2 will be 100 displayed, and the danger signal D at the entrance of block T^3 will be displayed. If, by the time the contact shoe M of the train in block T^2 , reaches the contact shoe L^2 , block T^3 is still occupied, the magnet of 105 secondary relay SR^2 will still be deenergized and the shoe M of the train in block T^2 making contact with contact rail section L^2 , will complete the circuit which shunts out 110 train relay TR, so stopping the train.

By connecting conductor 10 to one of the axle bearings of the train and thence to the magnet of relay TR, I insure that if either of the wires leading to this axle bearing be broken, the relay TR will be deenergized 115 and the train brought to rest. It will be apparent that if the wire 11 or the wire leading from the shoe M back to battery TB, be broken, the relay will also be deenergized and the train brought to rest. It 120 will be apparent that if for any reason the shoe M be torn from the train, the relay TR will be deenergized and therefore the train will be brought to rest.

One purpose of passing the controlling 130

circuit of each secondary relay SR^1 , SR^2 , etc., through the contact rail section L^1 , L^2 , etc., of the block next ahead, is to insure that if for any reason one of these contact rails should be displaced an indication of such displacement will be given. If, for example, contact rail section L^3 should be displaced seriously, the effect will be, inevitably, to break the connection of that rail section to conductors 23, and 19, and thereby to break the controlling circuit of relay SR^2 of the block next in rear. Therefore, when a train next enters block T^2 the magnet of relay SR^2 cannot be energized and therefore the train which has so entered block T^2 will be brought to rest, indication being thus given of trouble in block T^3 .

In Fig. 2 I illustrate a system which is similar to that of Fig. 1, except that the circuits are somewhat simplified by the omission of certain of the features of the circuits of Fig. 1. In Fig. 2, the contacts 20 of the secondary relay SR^1 , SR^2 , etc., are omitted, also the contacts 25 of those relays, and the controlling circuit of the secondary relay of each block passes from ground G^1 , G^2 , etc., of the corresponding block, through the rear contact 31 of the corresponding main relay MR^1 , MR^2 , etc., and through the magnet of the said secondary relay and thence through the contact 29 of the corresponding delay action relay DR^1 , DR^2 , etc., and thence through conductor 28 to contact 27 of the main relay MR^1 , MR^2 , etc., of the block next in advance, and thence through battery 24 to ground. Passing the controlling circuit of each secondary relay through contacts of the secondary relay of the block in advance as well as through contacts of the main relay of such block in advance has certain advantages, in that a certain degree of additional protection may be secured thereby; but in many cases such additional protection is unnecessary, and the simplified circuit shown in Fig. 2 may be used.

Passing the controlling circuit of each secondary relay through the contact rail section L^1 , L^2 , etc., of the block next in advance, as is indicated in Fig. 1, also has certain advantages, as explained above, but in some cases this may not be deemed necessary, and therefore in Fig. 2 the controlling circuit of each secondary relay is not passed through the contact rail section L^1 , L^2 , etc., of the block next in advance.

In the circuits shown in Fig. 2, instead of passing the battery conductor 10 of the rails TR through one of the axle bearings, as in Fig. 1, I have connected that conductor 10 to one of the axle bearings, and therefore to the corresponding axle and wheels, by a conductor 12. The operation of the circuit of the controlling circuit of relay TR is the same as in Fig. 1, except that should the conductor 12 be broken deenergization of re-

lay TR does not follow. However, in most cases this conductor 12 can be led and protected in such manner that there is no probability of its being broken. In Fig. 2 I also show that suitable switches 32, controlled by hand or otherwise, may be placed in the controlling circuits of the secondary relays, to prevent the operation of such secondary relays to break the connection between the contact conductors L^1 , L^2 , etc. and the track rails of the corresponding blocks, and so to cause the arrest of a train which may contact with one of the contact conductors L^1 , L^2 , etc. when the corresponding switch 32 is open. These switches 32 may be employed with advantage at crossings, draw bridges, switches, etc., to prevent passage of trains through a block when the crossing gates are raised, or the draw bridge open, or a switch open. In Fig. 2 I further indicate that the train relay TR may control a cab signal, there indicated as a semaphore arm 33, which arm is connected by a rod 34 to the plunger 35 of a coil 36 connected in parallel with holding coil H ; a spring 37 tending to press the semaphore arm to danger position against the pull of coil 36.

The contact rail sections or conductors L^1 , L^2 , etc., may be of any suitable length and may be placed wherever thought best in their respective blocks. In Fig. 1 I have shown each such contact conductor located a short distance beyond the entrance to its corresponding block (such distance being, preferably, a distance such that in most cases the trains may be brought to rest by prompt application of brakes upon first sight of a caution or danger signal, before such contact conductor is reached); but in Fig. 2 I have shown each such contact conductor located near the entrance of the next succeeding block, a location which seems preferable when caution signals are employed; for the engineer of a train about to enter a block will naturally bring his train under control if he sees the caution signal of that block displayed, and will bring his train to rest before he reaches the contact rail section L^1 , L^2 , etc., of that block, if he finds the danger signal of the next block displayed, so that the operation of the automatic stopping device described is required only in the event that the engineer permits his train to proceed far enough into a block to make contact with the contact conductor L^1 , L^2 , etc., of that block notwithstanding that the danger signal of the block next ahead is displayed. By locating these contact conductors L^1 , L^2 , etc., near the entrance of the block next ahead but sufficiently distant therefrom to insure a train being brought to rest without passing a danger signal, trains are permitted to proceed with caution past a caution signal until arrested at one of the contact conductors 120

5 L^1, L^2 , etc., provided the block ahead be still occupied, and thereby the train capacity of the system is considerably increased as the contact conductors are each located just beyond the entrance of the corresponding block, and without diminution of the factor of safety.

10 In general, when the contact conductors L^1, L^2 , etc., are located near the entrance of the block in advance, as indicated in Fig. 2, the danger signal of the block in advance will be visible, if displayed, before reaching such contact conductor; but when this is not the case, additional caution signals C' may 15 be provided about opposite the corresponding contact rail sections L^1, L^2 , etc., and in the same circuits with the danger signals next ahead.

20 The secondary relays do not necessarily operate on normally open circuit. In Fig. 3 I illustrate circuits in which the secondary relays, there designated by characters SR^1, SR^2 , etc., operate upon normally closed circuit. A simplified arrangement of circuits, 25 in general similar to those of Fig. 2, is illustrated. Each secondary relay has two magnet coils, one in a circuit passing from ground G^1, G^2 , etc., of the block in advance 30 through a rear contact 38 of the main relay MR^1, MR^2 , etc., of such block in advance and through conductor 28 to the coil 39 of such secondary relay, and thence to ground; the other coil, 40, of such secondary relay 35 being in a circuit passing from ground through spring contact points 41 and 42 of the corresponding delay action relay DR^1, DR^2 , etc., and through battery 24 and said coil 40 to ground. In this arrangement, 40 each main relay MR^1, MR^2 , etc., controls the circuit of its corresponding secondary relay by controlling the corresponding delay action relay, DR^1, DR^2 , etc., and these delay action relays are controlled by front 45 contacts 43 of the corresponding primary or main relays MR^1, MR^2 , etc. The operation of the circuits shown in Fig. 3 is in effect the same as that of the circuits shown in Fig. 2. The delay action relays of Fig. 50 3 are relays which open their contacts a predetermined interval after the magnets of said relays are deenergized.

In this specification I use the term "train" to designate anything from a single 55 car or locomotive to a train composed of a number of cars; and I use the term "relay" as inclusive of any mechanically actuated or electrically actuated circuit breaker or circuit closer.

60 What I claim is:—

1. A railway train controlling system comprising in combination a track divided into blocks, a contact conductor for each block, a train contact device adapted to make 65 contact with such contact conductors, a train

circuit comprising electrically controlled train-controlling means, a source of electric energy and a part electrically connected with a track rail, a primary relay for each block, controlled by trains passing along 70 said track, a secondary relay for each block, a partial circuit controlled by said secondary relay and which when completed closes connection between the contact conductor for that block and the track rail of that block, 75 and an operating circuit for each such secondary relay controlled by the corresponding primary relay and by the primary relay of a block in advance, and arranged to cause such secondary relay to break the said partial circuit controlled by it when the corresponding primary relay is in a condition corresponding to an occupied condition of its corresponding block, and when the primary relay of the said advance block is in a condition corresponding to clear condition of 80 its corresponding block.

2. A railway train controlling system comprising in combination a track divided into blocks, a contact conductor for each 90 block, a train contact device adapted to make contact with such contact conductors, a train circuit comprising electrically controlled train-controlling means, a source of electric energy and a part electrically connected with a track rail, a primary relay for each block, controlled by trains passing along said track, and means normally closing connection between the contact conductor of each block and the track rail of the 100 corresponding block, such means arranged to open such connection between said contact conductor and track rail when a train enters said block, provided the block ahead is clear. 105

3. A railway train controlling system comprising in combination a track divided into blocks, a contact conductor for each block, a train contact device adapted to make contact with such contact conductors, a train circuit comprising electrically controlled train-controlling means, a source of electric energy and a part electrically connected with a track rail, a primary relay for each block, controlled by trains passing along said track, means normally closing connection between the contact conductor of each block and the track rail of the corresponding block, such means arranged to open such connection between said contact conductor and track rail after a train enters said block, provided the block ahead is clear, and means preventing opening of such connection for a predetermined interval following the entry of such train into such block. 110 115 120 125

4. A railway train controlling system comprising in combination a track divided into blocks, a contact conductor for each block, a train contact device adapted to make contact with such contact conductors, a train 130

circuit comprising electrically controlled train-controlling means, a source of electric energy and a part electrically connected with a track rail, a primary relay for each block, controlled by trains passing along said track, normally closing connection between the contact conductor of each block and the track rail of the corresponding block, such means arranged to open such connection between said contact conductor and track rail after a train enters said block, provided the block ahead is clear, and a delay-action relay arranged to prevent the opening of such connection for a predetermined interval following the entry of such train into such block.

5. A railway train controlling system comprising in combination a track divided into blocks, a contact conductor for each block, a train contact device adapted to make contact with such contact conductors, a train circuit comprising electrically controlled train-controlling means, a source of electric energy and shunt connections to said train contact device and to a track rail, a primary relay for each block, means for operating the same operated by trains passing along said track, a secondary relay for each block, a circuit controlled by said secondary relay and which when completed closes connection between the contact conductor for that block and the track rail of that block with which the said train circuit is connected, an operating circuit for each such secondary relay controlled by the corresponding primary relay and by the primary relay of a block in advance, and arranged to cause such secondary relay to break the said circuit controlled by it when the corresponding primary relay is in a condition corresponding to an occupied condition of its corresponding block, and when the primary relay of the said advance block is in a condition corresponding to clear condition of its corresponding block, and means for delaying the breaking of the said connection between the contact conductor and track rail for a predetermined interval following the entry of a train into the corresponding block.

6. A railway train controlling system comprising in combination a track divided into blocks, a contact conductor for each block, a train contact device adapted to make contact with such contact conductors, a train circuit comprising electrically controlled train-controlling means, a source of electric energy and shunt connections to said train contact device and to a track rail, a primary relay for each block, means for operating the same operated by trains passing along said track, a secondary relay for each block, a circuit controlled by said secondary relay and which when completed closes connection between the contact conductor for that block

and the track rail of that block with which the said train circuit is connected, an operating circuit for each such secondary relay controlled by the corresponding primary relay and by the primary relay of a block 70 in advance, and arranged to cause such secondary relay to break the said circuit controlled by it when the corresponding primary relay is in a condition corresponding to an occupied condition of its corresponding block, and when the primary relay of the said advance block is in a condition corresponding to clear condition of its corresponding block, and a delay action relay for each block controlled by the primary relay of that block and controlling the operating circuit of the secondary relay of such block and arranged to prevent operation of such secondary relay for a predetermined interval following the entry of a train into the corresponding block. 85

7. A railway train controlling system comprising in combination a track divided into blocks, a contact conductor for each block, a train contact device adapted to make contact with such contact conductors, train controlling means arranged to be operated by closing of contact between such train contact device and one of said contact conductors, means for rendering the closing of such contact ineffective in the event that at the time of closing such contact the block in advance is clear, and means for rendering effective the closing of such contact between the train contact device and contact conductor, notwithstanding that such block ahead be clear, if such contact be closed within a predetermined interval following the entry of the train into the corresponding block. 90 95 100

8. A railway train controlling system comprising in combination a track divided into blocks, a contact conductor for each block adapted to make contact with contact devices carried by trains passing over said track, a primary relay for each block, means for operating the same operated by trains passing along said track, a secondary relay adapted to open and close connection between the contact conductor of each block and one of the track rails of that block, such secondary relay being controlled by the primary relay of its own block, and also by the primary relay of a block in advance, and means for delaying action of said secondary relay for a predetermined time following the entry of the train into the corresponding block. 105 110 115 120

9. A railway train controlling system comprising in combination a track divided into blocks, a contact conductor for each block adapted to make contact with contact devices carried by trains passing over said track, a primary relay for each block, means for operating the same operated by trains passing along said track, a secondary relay 130

adapted to open and close connection between the contact conductor of each block and one of the track rails of that block, such secondary relay being controlled by the primary relay of its own block, and also by the primary relay of a block in advance, means for delaying action of said secondary relay for a predetermined time following the entry of the train into the corresponding block, and block signaling means for each block controlled by the primary relay of that block.

10. A railway train controlling system comprising in combination a track divided into blocks, a contact conductor for each block adapted to make contact with contact devices of trains passing over that track, a primary relay for each block, means for operating the same operated by trains passing along said track, a secondary relay for each block normally closing connection between the contact conductor of that block and one of the track rails, circuits controlling said secondary relays and controlled by the primary relays, whereby each secondary relay is controlled both by the corresponding primary relay and by the primary relay of a block in advance, and is adapted to break the connection between the contact conductor and track rail controlled by it after the corresponding primary relay has operated consequent upon the entry of a train into the corresponding block, and provided the block ahead be clear, and means for delaying such action of each secondary relay for a predetermined time following such operation of the corresponding primary relay.

11. A railway train controlling system comprising in combination a track divided into blocks, a contact conductor for each block adapted to make contact with contact devices of trains passing over that track, a primary relay for each block, means for operating the same operated by trains passing along said track, a secondary relay for each block normally closing connection between the contact conductor of that block and one of the track rails, circuits controlling said secondary relays and controlled by the primary relays, whereby each secondary relay is controlled both by the corresponding primary relay and by the primary relay of a block in advance, and is adapted to break the connection between the contact conductor and track rail controlled by it after the corresponding primary relay has operated consequent upon the entry of a train into the corresponding block, and provided the block ahead be clear, and a delay action relay for each block, controlled by the primary relay of that block, and controlling the controlling circuit of the secondary relay of that block, and arranged to delay, for a predetermined interval, action of the corresponding secondary relay following action of the corre-

sponding primary relay consequent upon entry of a train into the corresponding block.

12. A railway train controlling system comprising in combination a track divided into blocks, a contact conductor for each block adapted to make contact with contact devices of trains passing over said track, a primary relay for each block, a normally closed track circuit controlling each primary relay, and adapted to be short-circuited by a train entering that block, a secondary relay for each block normally closing a connection between the contact conductor of that block and one of the track rails, a normally open circuit for controlling each secondary relay, such circuit controlled by a rear contact of the corresponding primary relay and by a front contact of the primary relay of a block in advance, and a delay action relay likewise controlling such secondary relay circuit and itself controlled by a rear contact of the corresponding primary relay, such delay action relay arranged to prevent completion of the controlling circuit of the corresponding secondary relay for a predetermined interval following retraction of the armature of the corresponding primary relay.

13. A railway train controlling system comprising in combination a track divided into blocks, a contact conductor for each block adapted to make contact with contact devices of trains passing over said track, a primary relay for each block, a normally closed track circuit controlling each primary relay, and adapted to be short-circuited by a train entering that block, a secondary relay for each block normally closing a connection between the contact conductor of that block and one of the track rails, a normally open circuit for controlling each secondary relay, such circuit controlled by a rear contact of the corresponding primary relay and by a front contact of the primary relay of a block in advance, a delay action relay likewise controlling such secondary relay circuit and itself controlled by a rear contact of the corresponding primary relay, such delay action relay arranged to prevent completion of the controlling circuit of the corresponding secondary relay for a predetermined interval following retraction of the armature of the corresponding primary relay, and block signals likewise controlled by the said primary relays.

14. A railway train controlling system comprising in combination a track divided into blocks, a contact conductor for each block adapted to contact with train contact devices of trains passing over said track, train-controlling means arranged to be actuated by closing of contact of such train contact devices with such contact conductors, means for rendering the closing of such con-

- tact ineffective in the event that at the time of closing such contact the block in advance is clear, and means for rendering effective the closing of such contact between the train 5 contact device and contact conductor, notwithstanding that such block ahead be clear, if such contact be closed within a predetermined interval following the entry of a train into the corresponding block.
- 10 15. A railway train controlling system comprising in combination a track divided into blocks, a contact conductor for each block located near the entrance of the next succeeding block, a train contact device 15 adapted to make contact with such contact conductors, train controlling means arranged to be operated by closing of contact between such train contact devices and one of said contact conductors, a primary relay 20 for each block, a track circuit for each primary relay controlling the same, a danger signal controlled by each primary relay, a caution signal controlled by each primary relay and located in proximity to the contact 25 conductor of the block next in rear, and a secondary relay for each block, controlled by the primary relay of that block and also by the primary relay of the block next in advance, and arranged to be operated by its 30 primary relay, to make ineffective contact between a train contact device and the contact conductor of the corresponding block, upon the operation of the corresponding primary relay consequent upon the entry of
- a train into that block, and provided the block next in advance be clear.
16. A railway train controlling system comprising in combination a track divided into blocks, a contact conductor for each block, a train contact device adapted to make contact with such contact conductors, train controlling means arranged to be operated by closing of contact between such train contact device and one of said contact conductors, a primary relay for each block, 45 a track circuit for each primary relay controlling the same, danger and safety signals for each block controlled by the corresponding primary relay, a secondary relay for each block controlled by the primary relay 50 of that block and by the secondary relay of a block in advance, said secondary relays each provided with means for rendering ineffective the closing of contact between a train contact device and the corresponding contact conductor of that block, upon the operation of the corresponding primary relay consequent upon the entry of such train 55 into that block, and provided the block next in advance be clear.

In testimony whereof I have signed this specification in the presence of two subscribing witnesses.

JOHN C. McDONALD.
